UNITED STATES PATENT OFFICE.

JAMES T. GUTHRIE, OF LEESBURG, OHIO.

TELEGRAPH-KEY.

SPECIFICATION forming part of Letters Patent No. 267,878, dated November 21, 1882.
Application filed September 13, 1882. (No model.)

To all whom it may concern:

Be it known that I, JAMES T. GUTHRIE, of Leesburg, in the county of Highland and State of Ohio, have invented certain new and useful Improvements in Telegraphic Keys; and I do hereby declare that the following is a full, clear, and exact description thereof, reference being had to the accompanying drawings, and to the letters of reference marked thereon, which form part of this specification, and in which—

Figure 1 is a top view of my improvement in telegraphic keys. Fig. 2 is a side elevation of the key and its stand, looking from the right-hand side thereof. Fig. 3 is a transverse section taken in a vertical plane indicated by the dotted line *xx* on Figs. 1 and 2.

The nature of my invention consists in a telegraphic key which is provided with a circuit-closer which is independent of the key, and which will be fully set forth in the following description, when taken in connection with the annexed drawings, which I have above referred to.

25 The letter A designates the base of the instrument, and B a frame, which is secured upon the base A. C designates the well-known key-lever, which may be pivoted to the standards D of the frame B, with set and jam nuts in the usual well-known manner. The shortest arm of this key-lever has applied to it the usual set-screw and jam-nut, the point *a* of which set-screw is brought in contact with a base, which is electrically connected with the 30 post F by a wire in the usual manner. The opposite pole is electrically connected with a device which is secured to the front end of the frame B by a wire, N, which is electrically connected to the post F'. This arrangement establishes an electrical connection through the 35 line when the key-lever is depressed.

Now I shall describe my improvement, which consists in a circuit-closing lever, G, which articulates at the rear end about the well-known pivot by means of a nut, holding it in place on one side of the key-lever, and allowing sufficient play. On top of the key C, at the fulcrum thereof, is secured one end of a spring, H, the other end of which bears on the lip *b* of 40 the circuit-closing lever G, which always keeps the circuit closed, except when the key is being manipulated. The circuit-closing lever G is of

sufficient length to bring the button G' (which is of curved form and which is a non-conductor of electricity) directly over the button on the 55 key proper.

In operating the device the fingers of the human hand are slipped between the two buttons, thus opening the circuit, which is then held open while operating. The circuit-closing lever G is guided by means of a side loop, *c*, secured to the side of the key. On the lower edge of the lever G is formed a tapered or wedge-shaped extension, *d*, which is adapted to fit closely into a wedge-shaped opening formed 60 between two jaws, *e e*, fixed to the frame B, thus forming a triple dust-proof connection on both the sides and bottom of the said wedge-extension *e'*.

The usual spiral spring, J, is employed for 70 the purpose of raising the longest arm of the key-lever, and at the shortest arm of this lever is applied the well-known adjusting-screw and jam-nut.

Having thus fully described my invention, 75 what I claim as new, and desire to secure by Letters Patent, is—

1. The combination, with a telegraphic key, of a circuit-closing lever pivoted at its rear end to the fulcrum-rod of said key, the spring 80 H acting on this lever, the button on the front end thereof, the wedge-shaped extension and the bifurcated bearing for receiving said extension, all constructed and operating substantially in the manner and for the purposes 85 described.

2. The combination of the pivoted key, provided with a button on one arm, the supporting-frame thereof, the adjusting-screw therefor, the spring J, the circuit-closing lever G, the curved button G' on the free end of this lever, the guide for the latter, and the holding-down spring, all adapted to operate in union, substantially in the manner and for the purposes described.

In testimony that I claim the foregoing as my own I affix my signature in presence of two witnesses.

JAMES T. GUTHRIE.
